UNITED STATES PATENT OFFICE.

GEORGE W. CHALMERS, OF SUMMIT, AND FRANK E. WILSON, OF ARGO, ILLINOIS,
ASSIGNORS TO INTERNATIONAL PATENTS DEVELOPMENT COMPANY, OF WIL-
MINGTON, DELAWARE, A CORPORATION OF DELAWARE.

BAIL-PLACING MACHINE.

Application filed February 5, 1925. Serial No. 7,058.

To all whom it may concern:

Be it known that we, GEORGE W. CHALMERS and FRANK E. WILSON, citizens of the United States, residing at Summit and Argo, in the county of Cook and State of Illinois, respectively, have invented certain new and useful Improvements in Bail-Placing Machines, of which the following is a specification.

- 10 This invention relates to a machine for automatically positioning bails on cans or similar receptacles, provided with recesses or ears for receiving the hooked ends of the bails.
- 15 After a can has been provided with a diametrically opposed pair of recesses or holes near its upper edge, or with bail-ears provided with such recesses, it is necessary to spring into place a bail, having inturned hooked ends which engage in these recesses.
- 20 The principal object of the present invention is to provide an improved machine for automatically positioning these bails in the bail ears or recesses on the cans.
- 25 A further object is to provide an improved conveyor for supporting the cans by their ears, in bail-receiving position, and intermittently moving these cans forwardly from station to station, a bail being positioned within
- 30 the can ears, while a can is resting at one of these stations.

A further object is to provide improved means for feeding the cans to the conveyors, at a preceding station.

- 35 A further object is to provide an improved means for feeding the bails to the bail-positioning apparatus.
- 40 A further object is to provide an improved means for spreading the bail ends and guiding the bail into position upon the can.

A further object is to provide means for carrying away the assembled cans and bails, after they are released from the conveyor.

- 45 Numerous other objects and advantages of this invention will be apparent from the following detailed description of one approved form of the apparatus.

In the accompanying drawings:

- 50 Fig. 1 is a side elevation of the apparatus, not including the can feeding mechanism.

Fig. 2 is a plan view of this portion of the apparatus.

Fig. 3 is a vertical transverse section, on

an enlarged scale, taken substantially on the line 3—3 of Fig. 1.

55

Fig. 4 is an enlarged vertical section taken substantially on the line 4—4 of Fig. 3.

Fig. 5 is an enlarged vertical section, showing a portion of the bail positioning apparatus, the view being taken substantially on the line 5—5 of Fig. 2.

60

Fig. 6 is a perspective view of the bail-feeder head, and the bail-spreader.

65

Fig. 7 is an enlarged detail view, partially in section through one of the devices for advancing the bails along the bail-feeder. This view is taken substantially on the line 7—7 of Fig. 3.

70

Fig. 8 is a detail plan view of one of the actuating mechanisms for forcing the bail-ends into engagement with the bail-ears.

75

Fig. 9 is a perspective view of one of the ear-supporting pockets.

Fig. 10 is a detail elevation of the cam actuating mechanism for the bail-spreader. This view is taken looking from the left at the upper portion of Fig. 3.

80

Fig. 11 is a side elevation of the can-feeding mechanism. This view is substantially a continuation of the right-hand end of Fig. 1.

85

Fig. 12 is a plan view of the apparatus shown in Fig. 11.

90

Fig. 13 is a transverse vertical section, on a larger scale, taken substantially on the line 13—13 of Fig. 11.

95

The entire apparatus may be considered as composed of the following main portions: A conveyor A for holding the cans and moving them intermittently from one station to another, through the apparatus; a mechanism B for feeding the cans to the conveyor; a mechanism C for feeding bails to the bail-placing station; a mechanism D for placing these bails in the can ears; and a conveyor E for carrying away the assembled cans. These several devices will first be described in detail in the order mentioned above.

100

In the upper portion of the supporting framework 1, are arranged four similar parallel horizontal channels or guideways 2, 3, 4 and 5. The inner and outer runs of a looped conveyor chain 6 are supported and guided by the runways 2 and 3, respectively, and a similar conveyor chain 7 is supported in the runways 4 and 5. The looped ends of chain 6 are carried by sprocket wheels 8 and

105

9, mounted on vertical shafts 10 and 11, respectively. Chain 7 is similarly supported on sprocket wheels 12 and 13 mounted on vertical shafts 14 and 15 respectively. By 5 means of the intermeshing gear wheels 16 and 17, on the shafts 10 and 14, the chains 6 and 7 are caused to move in unison, but in opposite directions, so that their parallel inner runs will travel together and in the 10 same direction, whereby the cans may be transported in the space between the inner runways 2 and 4, as hereinafter described.

Each chain 6 and 7 is provided at spaced intervals with pocket members 18, which are 15 mounted on the upper portions of the chain, so that the can-ear-carrying portions 19 of these pocket members, may project inwardly over the inner flanges of the runways 2 and 4. The inner face of each pocket is curved 20 as at 20, to fit the outer cylindrical surface of one of the cans, and the inner runs of the conveyor chains are spaced at such a distance apart that the diametrically opposed sides of the can will fit easily between a pair of 25 these opposed pocket members, as indicated in Fig. 2. The pocket 21 in each of these members 18, is so shaped (as best shown in Fig. 8), as to receive and support one of the ears 22 on the can 23. In this manner, 30 the can will be supported in upright position by its ears in an opposed pair of these pocket members 18, and will be carried along in this position between the runways 2 and 4.

The main horizontal drive shaft 24 carries 35 a pulley 25 at one end from which power is obtained from any suitable source. The vertical drive shaft 26 is driven from shaft 24 through bevel gears 27 and 28. A second vertical shaft 29 is driven from shaft 26 40 through the reducing gears 30 and 31. At diametrically opposite points upon the upper surface of gear 31, are mounted two similar pins or rollers 32, which engage in a series of radial slots 33, in a disc 34 carried 45 by a vertical shaft 35, also mounted in the framework 1. A gear 36 on shaft 35 drives the gear 37 on the shaft 10 heretofore described. The continuously revolving pins 32 engage at intervals with the slots 33 to 50 impart an intermittent forward movement to the disc 34, and thence through the gear connections hereinbefore described, to the two conveyor chains 6 and 7. Therefore, continuous rotation of the drive shaft 24 55 will, through the Geneva movement just described, cause the pairs of can-carrying pockets 18 to move forwardly (toward the left in Fig. 2), intermittently, resting at fixed intervals, at certain stations, along the 60 guideways 2 and 4.

A vertical shaft 38 (which drives the bail placing mechanism C), hereinafter described, 65 is driven from shaft 26 by means of the sprocket chain 39 connecting the sprocket 40 on shaft 26 with the sprocket 41 near the

lower end of shaft 38. A sprocket 42 on a vertical shaft 43 (see Figs. 11 and 12), is driven through chain 44 from a sprocket 45 on shaft 38. This sprocket chain 44 drives the can-feeding mechanism B, which will 70 now be described, referring particularly to Figs. 11, 12 and 13 of the drawings. A supply of the cans 23 with the ears attached, is maintained on the inclined runway 46, as indicated in Fig. 11. Located beneath one edge 75 of the discharge end of this runway 46, and directly above one station at which the pockets 18 rest, is a hollow cylindrical guide member 47, supported by a bracket 48 projecting upwardly from the frame-work 1. A 80 pair of vertical grooves 49, in this guide 47, are adapted to direct the can ears 22 downwardly into the pockets 21, in the pocket members 18. The opposite sides of the upper end of guide member 47 are cut away 85 as at 50 so as to guide the ears into the directing slots or grooves 49. Under the opposite edge of the discharge end of runway 46, is mounted a plunger 51, guided for vertical movement in a slideway 52. The upper 90 end of plunger 51 is curved as at 53, to support one end of the cylindrical portion of a can 23, when this can rolls off from runway 46, the opposite end of the can being similarly supported in one of the cutaway portions 50, of guide member 47. This position of one of the cans, is indicated in dotted lines in Fig. 13. A link 54 connects the plunger 51 with the free end of a lever 55, 100 the opposite end of which is pivoted at 56 to a stationary bracket 57. A roller 580 mounted at an intermediate point on lever 55, rests on the upper surface of a rotary cam 590, carried at the upper end of shaft 43. As shaft 43 is continuously rotated, the 105 plunger 51 will be intermittently lifted by means of the mechanism just described. The driving connections are so timed, that this plunger 51 will be elevated at the time a pair of pocket members 18 come to rest at their 110 station beneath the guide member 47. When the plunger 51 is elevated, the can 23 resting thereon will be tipped up (as indicated in dotted lines Fig. 13), into the cylindrical 115 guide 47, the curved portions 50 will guide the ears 22 into the slots 49, which will direct the ears downwardly into the pockets 21 in the members 18. At the next movement of the conveyor chains 6 and 7, this can will 120 be carried away to the next station, and a new pair of pockets brought into position beneath the guide slots 49. In the meantime, another can 23 has rolled down into position resting upon the plunger 51 and guide member 47. This cycle of events repeats 125 itself indefinitely, as long as a supply of cans is maintained upon the runway 46.

The mechanism C for feeding the bails to the positioning apparatus D, will now be described. The bails 58 are of the usual in- 130

verted U-shape, with inturned hooked ends 59. A feeder head 60, of a little more than semi-cylindrical cross section, and partially cut away as at 61, is supported in fixed position in the framework 1. This feeder head is best shown in Fig. 6. The feeder head is mounted in an inclined position, as shown in Fig. 1, so that the supply of closely assembled bails carried thereby, is adapted to 10 slide down toward the discharge end of the head. A removable bail-holder 62 may be formed of a plurality of suitably spaced rods held together by intermediate spiders 63. The reduced ends of the rods 62 at one end 15 of the bail-holder are adapted to be inserted in suitable sockets in the rear end of the feeder head 60, so that this bail-holder forms practically a continuation of the feeder head. When the bails from one bail holder are exhausted, this bail holder may be removed and replaced by another holder, carrying an assembled supply of bails. A follower 64 is adapted to move along a fixed guide or passageway 65, behind the assembled 20 group of bails. A cable 66, carrying a weight 67 at one end, is guided over a suitable system of pulleys and connected at its other end to the follower 64. The weight 67 tends to draw the follower towards the 25 discharge end of the feeder head, and hence force the bails to move down the inclined feeder. Mounted adjacent each side of the feeder head 60, is a stationary socket member 68, in which moves a toothed feeder plate 30 69, whose teeth 70 are of suitable size and configuration to individually grip and hold the several bails 58 carried near the discharge end of the feeder head. Springs 71, mounted between the plate 69 and one wall 35 of socket 68 yieldably urge the plate 69 toward the bails, and a second spring 72 secured at one end to the socket 68 and at the other end to the plate 69, tends to move the plate and the bails gripped thereby towards 40 the discharge end of the feeder head. A link 73 connects one end of the slide plate 69 with a lever 74 intermediately pivoted at 75, in the fixed framework. The other end 76 of lever 74 is adapted to be engaged by a cam 45 77 on a rock shaft 78, hereinafter described. As the shaft 78 oscillates, the slide 69 will be intermittently drawn back against the action of spring 72. The springs 71 will yield and allow the toothed plate 69 to 50 move back and grip a new series of bails. In this manner, the bails are constantly being fed forward toward the discharge end of the feeder head.

We will now describe the mechanism D for 55 positioning the bails upon the can. The vertical drive-shaft 38, hereinabove described, is connected at its upper end through bevel gears 79 and 80, with a horizontal shaft 81. Shaft 81 carries a cam wheel 82, having a cam slot 83 (see Fig. 4) in which engages 60 a pin or roller 84 on one end of a lever 85, intermediately pivoted at 86 in a bracket 87 extending upwardly from the stationary framework. A plunger or pusher-bar 88 is adapted to move vertically up and down through a fixed slideway 89. An adjustable link 90 at the upper end of pusher-bar 88 carries a pin 91 engaging in a slot 92 in the other end of the lever 85 previously described. The lower end of pusher bar 88 65 has a pair of notched shoulders 93, adapted to engage the upper portion of one of the bails 58.

A bail-spreader assembly 94 is mounted for vertical reciprocating movement in the end of feeder head 60. This spreader assembly comprises a pair of similar oppositely disposed spreader plates 95, each having a lower tapered end portion 96, adapted to be moved down into one of the pockets 21, behind the can-ear 22 carried therein. Each spreader plate 95 has a guide slot 97, in which one of the hooked end portions 59 of the bail is engaged and directed downwardly into the pocket 21. In the back of each pocket 21 in pocket-member 18, is a vertical slot 98 for receiving the hooked end of the bail, which is guided downwardly thereinto, by slot or groove 97 in spreader plate 95. A lever arm 99, mounted on rock shaft 78 is connected at its outer end to the spreader assembly 94, so that when rock shaft 78 is oscillated, the spreader assembly 70 will be moved up and down, so as to carry the ends 96 of the spreader plates into or out of the pockets 21. A crank arm 100, on one outer end of rock shaft 78, is connected to the lower end of a push rod 101, adapted to reciprocate vertically through a bearing 102, carried by the framework. The upper end of rod 101 is slotted as at 103, (see Fig. 10), to move up and down around and be guided by the rotary shaft 81, and carries a pin or roller 104, which moves in a cam slot 105 in one face of a cam disc 106 secured to the shaft 81. By means of this cam, continuous rotation of the shaft 81 will cause the bail spreader to be moved intermittently into and out of connection with the pocket members 18. 100

Pivoted near the lower end of the bail- 105 pusher 88 is a link or latch 130, having a lower inturned hooked end 131 adapted to cooperate with the notched shoulders 93 to form a pocket in which is supported the upper bowed end of one of the bails 58, as it slides from the feeder-head 60. A spring 132 normally holds this hooked end yieldably in place beneath the bail, and, when the bail-pusher is in its uppermost, or bail-receiving position, as shown in Figs. 3 and 4, a cross-bar 133 on the link 130 will be engaged by a pair of fixed cams 134 on the fixed guides 89 so as to positively hold the hooked end 131 in bail-supporting position. 110

We will now describe the mechanism D for 115 positioning the bails upon the can. The vertical drive-shaft 38, hereinabove described, is connected at its upper end through bevel gears 79 and 80, with a horizontal shaft 81. Shaft 81 carries a cam wheel 82, having a cam slot 83 (see Fig. 4) in which engages 120 a pin or roller 84 on one end of a lever 85, intermediately pivoted at 86 in a bracket 87 extending upwardly from the stationary framework. A plunger or pusher-bar 88 is adapted to move vertically up and down through a fixed slideway 89. An adjustable link 90 at the upper end of pusher-bar 88 carries a pin 91 engaging in a slot 92 in the other end of the lever 85 previously described. The lower end of pusher bar 88 125 has a pair of notched shoulders 93, adapted to engage the upper portion of one of the bails 58.

A bail-spreader assembly 94 is mounted for vertical reciprocating movement in the end of feeder head 60. This spreader assembly comprises a pair of similar oppositely disposed spreader plates 95, each having a lower tapered end portion 96, adapted to be moved down into one of the pockets 21, behind the can-ear 22 carried therein. Each spreader plate 95 has a guide slot 97, in which one of the hooked end portions 59 of the bail is engaged and directed downwardly into the pocket 21. In the back of each pocket 21 in pocket-member 18, is a vertical slot 98 for receiving the hooked end of the bail, which is guided downwardly thereinto, by slot or groove 97 in spreader plate 95. A lever arm 99, mounted on rock shaft 78 is connected at its outer end to the spreader assembly 94, so that when rock shaft 78 is oscillated, the spreader assembly 130 will be moved up and down, so as to carry the ends 96 of the spreader plates into or out of the pockets 21. A crank arm 100, on one outer end of rock shaft 78, is connected to the lower end of a push rod 101, adapted to reciprocate vertically through a bearing 102, carried by the framework. The upper end of rod 101 is slotted as at 103, (see Fig. 10), to move up and down around and be guided by the rotary shaft 81, and carries a pin or roller 104, which moves in a cam slot 105 in one face of a cam disc 106 secured to the shaft 81. By means of this cam, continuous rotation of the shaft 81 will cause the bail spreader to be moved intermittently into and out of connection with the pocket members 18. 140

As one of the bails 58 passes off from the end of feeder head 60, its upper bowed portion will be engaged by the notched shoulders 93 at the lower end of bail-pusher 88 and the hooked end 131 of link 130, and its lower hooked ends 59 will be engaged in the guide grooves 97 in the spreader plates 95. The cam drive mechanism is so timed that when a pair of pocket members 18, carrying the can 23 by its ears 22, comes to rest at the bail-positioning station, the bail spreader 94 and the bail pusher 88 will simultaneously be projected downwardly, carrying one of the bails 58, until the bail spreader ends 96 are positioned behind the ears 22, in the pockets 21. The bail pusher 88 will continue to move downwardly, forcing the hooked ends of the bail outwardly along the grooved spreader plates, through the slots 98 in pocket members 18, until the hooked ends 59 of the bail snap into place within the holes in the bail ears.

The spring action of the bail may be sufficient to cause the hooked ends 59 to engage in the holes in the bail ears, but we have also provided positive means for insuring this engagement. Each pocket member 18 contains a plunger 107, having a stem 108 projecting through the rear wall of member 18, with a cam engaging head 109 on its outer end. An expansion spring 110 surrounding stem 108, between head 109 and the rear face of member 18, normally holds the plunger 107 in retracted position. When the plunger is forced inwardly against the action of spring 110, it will engage the outer end portion of the bail 58 and force the hooked end 59 into the hole in the bail-ear. A small bell crank 111, pivoted at 112 on a portion of the stationary framework, carries at one end a cam-head 113, adapted to engage the head 109 on any one of the plungers 107. The opposite end of the bell crank 111, carries a roller 114, which engages the peripheral surface of rotary cam 115, carried at the upper end of vertical shaft 116. The two similar shafts 116, at the two sides of the conveyor, are geared together to rotate in unison by a sprocket chain connection 117. A second sprocket chain drive 118, connects one of these shafts 116, with a sprocket 119 on the lower end of the vertical drive shaft 38 hereinabove described. The timing of these drive connections is such that immediately after the hooked ends 59 of a bail have been brought into engagement with the holes in the ears 22 on the can 23, then resting at this station, the bell cranks 111 will be operated to force the plungers 107 inwardly, and positively engage the hooked ends 59 with the can-ears.

On the upward stroke of bail-pusher 88, after a bail 58 has been positioned in engagement with a can, the spring 132 will

yield and allow the beveled end of hooked arm 131 to snap out of engagement with the bail 58 formerly supported thereby.

Of course, all of the above described operation takes place while one of the cans is resting at the station beneath the bail-positioning mechanism D. After the bail has been placed on the can, the conveyors 6 and 7 are again actuated to carry the assembled can and bail forwardly, and bring a new can into position beneath the bail placing mechanism. When the pocket members 18 reach the end of runways 2 and 4, and commence to turn outwardly about the sprockets 8 and 12, they will be disengaged from the ears 22, and the can 23 with the bail 58 assembled thereon, will drop onto the upper run of a conveyor belt 120, which forms part of the conveyor mechanism E, for carrying the assembled cans away from the bail-placing mechanism.

It will be noted that all of the mechanism A, B, C and D are driven in properly timed relation from the same drive shaft 24. The operation of the apparatus is continuous and entirely automatic, it only being necessary to replenish the supply of cans upon the runway 46, and to add a new loaded bail-holder 62 when the one previously used has become exhausted.

While some portions of this machine are designed to cooperate particularly with the bail-ears, as attached to the cans by a preceding operation. It is obvious that the bail positioning mechanism could be used to apply bails to cans or other receptacles simply provided with recesses or holes near their upper edges for receiving the hooked ends of the bails, the separate bail-ears being omitted.

The term "can" as used in the foregoing description and in the following claims is intended to cover pails, buckets, and other receptacles of this type, whether provided with a cover or not.

We claim—

1. A machine for placing bails on cans provided with bail-receiving ears, comprising a holder for a supply of bails, a conveyor for supporting the cans and moving them successively into position adjacent the bail holder, and means for moving and guiding a bail from the holder into engagement with the ears of a can.

2. A machine for placing bails on cans provided with bail-ears, comprising a holder for the cans, a holder for the bails, means for bringing the cans successively into operative relation to the bail-holder, and means timed with relation to the can-moving means for moving and guiding a bail from the bail-holder into engagement with the ears of a can.

3. A machine for placing bails on cans provided with bail-ears, comprising holders

for the can-ears having bail-guiding means, a second bail-guiding means movable into operative relation with one of the first guiding means, a holder for the bails, and means for moving a bail from the bail-holder, through the two guiding means into engagement with the can-ears.

4. A machine for placing bails on cans provided with bail-receiving ears, comprising a conveyor for supporting the cans by their ears, means for intermittently advancing the conveyor from station to station, means for feeding cans to the conveyor at one station, a bail-feeding means at a second station, and means at this second station for forcing a bail from the feeding means into engagement with the can-ears.

5. A machine for placing bails on cans provided with bail-receiving ears, comprising a conveyor for supporting the cans by their ears, means for intermittently advancing the conveyor from station to station, means for feeding cans to the conveyor at one station, a bail-feeding means at a second station, means at this second station for forcing a bail from the feeding means into engagement with the can-ears, and means for carrying away the assembled cans when released from the conveyor.

30 6. A machine for placing bails on cans provided with bail-receiving ears, comprising a conveyor for supporting the cans by their ears, means for intermittently advancing the conveyor from station to station, a bail-feeding means at one station, and means at this station for forcing a bail from the feeder into engagement with the ears of a can when resting at this station.

7. A machine for placing bails on cans provided with bail-receiving ears, comprising a conveyor for supporting the cans by their ears, means for intermittently advancing the conveyor from station to station, means for feeding cans to the conveyor at one station, means for positioning bails on the cans at a second station, and a conveyor belt having an upper horizontal run onto which the assembled cans are discharged from the first mentioned conveyor.

50 8. In a machine for placing bails on cans, a conveyor for the cans comprising a pair of similar chains, means for supporting and driving the chains so that the inner runs move parallel to and synchronously with one another in the same substantially horizontal plane, and a series of spaced ear-pockets carried by each chain, the can being suspended from the conveyor chains by having its two bail-ears resting in a pair of opposing ear-pockets.

9. In a machine for placing bails on cans, a conveyor for the cans comprising a pair of similar chains, means for supporting the chains so that the inner runs move parallel to and synchronously with one another in

the same substantially horizontal plane, a series of spaced ear-pockets carried by each chain, the can being supported from the conveyor chains by having its two bail-ears resting in a pair of opposing ear-pockets, and means for simultaneously imparting an intermittent forward movement to the conveyor chains.

10. In a machine for placing bails on cans, a conveyor for the cans comprising a pair of similar chains, the inner runs of which move parallel to and synchronously with one another, a series of spaced ear-pockets carried by each chain, the can being supported from the conveyor chains by having its two bail-ears resting in a pair of opposing ear-pockets, means for imparting an intermittent forward movement to the conveyor chains, whereby the cans pause at a plurality of stations, means at one station for feeding a can to the conveyor, and means at a second station for positioning a bail on the can.

11. In a machine for placing bails on cans, a conveyor for the cans comprising a pair of similar chains, the inner runs of which move parallel to and synchronously with one another, a series of spaced ear-pockets carried by each chain, each pocket having a concave inner face for engaging the cylindrical surface of the can, a recess for supporting the bail-ear, and a bail-guiding slot communicating with the recess.

12. In a machine for placing bails on cans, a conveyor for the cans comprising a pair of similar chains, the inner runs of which move parallel to and synchronously with one another, a series of spaced ear-pockets carried by each chain, each pocket having a recess for supporting the bail-ear and a bail-guiding slot communicating with the recess.

13. In a machine for placing bails on cans, a conveyor for the cans comprising a pair of similar chains, the inner runs of which move parallel to and synchronously with one another, a series of spaced ear-pockets carried by each chain, each pocket having a concave inner face for engaging the cylindrical surface of the can, a recess for supporting the bail-ear, and a bail-guiding slot communicating with the recess, a plunger for forcing the bail-end into engagement with an ear, and a spring for retracting the plunger.

14. In a machine for placing bails on cans provided with bail-ears, a pair of pocket-members for supporting the can by its ears, each member comprising an ear holding pocket, and a slot communicating with the pocket for directing a bail-end into engagement with the ear.

15. In a machine for placing bails on cans provided with bail-ears, a pair of pocket-members for supporting the can by its ears, each member comprising an ear holding pocket, and a slot communicating with the

6 pocket for directing a bail-end into engagement with the ear, and a plunger in the member for forcing the bail-end into the ear.

5 16. In a machine for placing bails on cans provided with bail-ears, a feeder-head for carrying a supply of bails, a vertically movable bail-spreader comprising guide members for the bail-ends, a movable supporting means for the can, means for moving the 10 bail-spreader into operative position with respect to the can-supporting means when the latter is resting beneath the bail-spreader, and means for subsequently moving a bail from the feeder down over the 15 bail-spreader into engagement with the can-ears.

17. In a machine for placing bails on cans provided with bail-ears, a feeder-head, a removable bail-holder attachable to the 20 feeder-head for carrying a supply of bails, and means for moving and guiding a bail from the feeder-head into engagement with a can.

18. In a machine for placing bails on cans 25 provided with bail-ears, a feeder-head, a removable bail-holder attachable to the feeder-head for carrying a supply of bails, means for moving the bails from the bail-holder to the feeder head, and means for 30 moving and guiding a bail from the feeder-head into engagement with a can.

19. In a machine for placing bails on cans provided with bail-ears, means for supporting the can, a bail-spreader movable into 35 engagement with the can-supporting means, and a bail-pusher for moving a bail over the bail-spreader into engagement with the can.

20. In a machine for placing bails on cans provided with bail-ears, means for supporting the can by its ears, a bail-spreader having portions movable into engagement with the ear-supporting means, and a bail pusher for moving a bail over the bail-spreader into engagement with the can.

45 21. In a machine for placing bails on cans provided with bail-ears, means for supporting the can by its ears, a bail spreader having portions movable into engagement with the ear-supporting means, and guide grooves 50 for directing the bail-ends into engagement with the can-ears, and a bail-pusher for moving a bail over the bail-spreader into engagement with the can.

22. In a machine for placing bails on cans 55 provided with bail-ears, means for supporting the can, a bail-spreader having discharge portions for directing the bail-ends into engagement with the can-ears, a bail-pusher, means for feeding a bail to the bail-spreader and bail pusher, and means for 60 moving the bail-spreader and bail-pusher and the bail carried thereby simultaneously until the bail-spreader is in position to guide the bail-ends into engagement with the ears, 65 and for subsequently moving the bail-pusher

only to move the bail over the bail spreader into engagement with the can.

23. In a machine for placing bails on cans, means for supporting the can comprising a pair of bail-ear-holding pockets, each pocket having a guide slot for the bail, a bail-spreader comprising diverging slideways terminating in projections adapted to fit within the pockets, means for moving the spreader into and out of the pockets, a 70 feeder for the bails, and a reciprocating bail-pusher adapted to push a bail from the feeder, over the spreader, through the guide slots into the bail-ears. 75

24. In a machine for placing bails on cans, means for supporting the can comprising a pair of bail-ear-holding pockets, each pocket having a guide slot for the bail, a bail-spreader comprising diverging slideways terminating in projections adapted to fit within the pockets, means for moving the spreader into and out of the pockets, a 80 feeder for the bails, and a reciprocating bail-pusher adapted to push a bail from the feeder, over the spreader, through the guide slots into the bail-ears, a rotary cam-shaft, and connections from this shaft to operate the spreader and pusher.

25. In a machine for placing bails on cans, means for supporting the can comprising a pair of bail-ear-holding pockets, each pocket having a guide slot for the bail, a bail-spreader comprising diverging slideways terminating in projections adapted to fit within the pockets, means for moving the spreader into and out of the pockets, a feeder for the bails, and a reciprocating bail-pusher adapted to push a bail from the feeder, over the spreader, through the guide slots into the bail-ears, and plungers 95 for positively forcing the bail ends into engagement with the ears. 100

26. In a machine for placing bails on cans, means for supporting the can comprising a pair of bail-ear-holding pockets, each pocket having a guide slot for the bail, a bail-spreader comprising diverging slideways terminating in projections adapted to fit within the pockets, means for moving the spreader into and out of the pockets, a 110 feeder for the bails, and a reciprocating bail-pusher adapted to push a bail from the feeder, over the spreader, through the guide slots into the bail-ears, a plunger in each pocket for forcing the bail-end into engagement with the ear, a spring for retracting the plunger, and a rotary cam for actuating the plunger. 115

27. In a machine for placing bails on cans, means for supporting the can comprising a pair of bail-ear-holding pockets, each pocket having a guide slot for the bail, means for intermittently moving the pockets, and a can carried thereby, from station to station, a bail-spreader located at one station comprising 120 125 130

- ing diverging slideways terminating in projections adapted to be moved into the pockets when at that station, a feeder for the bails, a reciprocating bail-pusher adapted 5 to push a bail from the feeder over the spreader through the guide slots and into the bail-ears on the can, a rotary cam-shaft, and connections from this shaft to operate the spreader and pusher.
- 10 28. In a machine for placing bails on cans, means for supporting the can comprising a pair of bail-ear-holding pockets, each pocket having a guide slot for the bail, means for intermittently moving the pockets, and a can carried thereby, from station to station, a bail-spreader located at one station comprising diverging slideways terminating in projections adapted to be moved into the pockets when at that station, a 15 feeder for the bails, a reciprocating bail-pusher adapted to push a bail from the feeder over the spreader through the guide slots and into the bail-ears on the can, a rotary cam-shaft, and connections from this shaft to operate the spreader and pusher, a plunger in each pocket for forcing the bail-end into engagement with the ear, a spring for retracting the plunger, and cam-operated means at the bail-placing station for operating the plunger.
- 20 29. In a machine for placing bails on cans, a slideway for the bails, a follower for moving the bails along the slideway, means for feeding the bails one by one from the slideway, a plurality of means for yieldably engaging the forward group of bails on the slideway at spaced points, spring means for urging these bail-engaging means toward the feeding means, and cam-operated means 25 for intermittently retracting the engaging means to grip a new group of bails.
- 25 30. In a machine for placing bails on cans, a slideway for the bails, comprising a fixed portion and a removable and replaceable section for holding a supply of bails, a follower for moving the bails along the slideway, means for feeding the bails one by one from the slideway, a plurality of means for yieldably engaging the forward 30 group of bails on the slideway at spaced points, spring means for urging these bail-engaging means toward the feeding means, and cam-operated means for intermittently retracting the engaging means to grip a new 35 group of bails.
- 30 31. In a machine for placing bails on cans, a slideway for the bails, a follower for moving the bails along the slideway, means for feeding the bails one by one from the slideway, a plurality of means positioned adjacent the slideway, each having a plurality of spaced teeth for engaging the individual bails of the group nearest the feeding means, springs for urging the toothed 40 means toward the bails, other springs for urging the toothed means toward the feeding means, and cam-operated means for intermittently retracting the toothed means against the action of the springs for gripping a new group of bails.
- 35 32. In a machine for placing bails on cans provided with bail-ears, a conveyor comprising ear-supporting pockets, a runway down which the cans are adapted to roll, and means for directing a can from the runway and guiding its ears into the pockets when the pockets are in can receiving position.
- 40 33. In a machine for placing bails on cans provided with bail-ears, a conveyor comprising ear-supporting pockets, a runway down which the cans are adapted to roll, means for guiding the can-ears into the pockets, and means for tilting a can from the runway into engagement with the guiding means when the pockets are in can receiving position.
- 45 34. In a machine for placing bails on cans, a conveyor comprising pairs of spaced ear-pockets for supporting cans having bail-ears thereon, means for intermittently advancing the conveyor for moving the pockets from station to station, a runway down which the cans are adapted to roll, a fixed guiding means at one station for directing the can-ears into a pair of pockets, a vertically reciprocating plunger for tipping a can into the guiding means, and means for actuating the plunger when a pair of ear pockets are 50 at the station.
- 50 35. In a machine for placing bails on cans, a conveyor comprising pairs of spaced ear-pockets for supporting cans having bail-ears thereon, means for intermittently advancing the conveyor for moving the pockets from station to station, a runway down which the cans are adapted to roll, an upright guiding means at one station having guide slots for directing the can-ears into the pockets, a vertically reciprocating plunger at that station, the plunger and guiding means having can holding recesses into which a can will roll from the runway, and means for actuating the plunger when a pair of pockets are at the station for tilting the can into the guiding means.
- 55 36. In a machine for placing bails on cans, a conveyor comprising pairs of spaced ear-pockets for supporting cans having bail-ears thereon, means for intermittently advancing the conveyor for moving the pockets from station to station, a runway down which the cans are adapted to roll, a fixed guiding means at one station for directing the can-ears into a pair of pockets, and means for moving a can from the runway into the guiding means when a pair of ear-pockets are at the station.
- 60 37. In a machine for placing bails on cans provided with recesses for receiving the

ends of the bails, a bail spreader, means for bringing the bail-spreader and a can into operative relation with one another, and a bail-pusher for moving a bail over the spreader into engagement with the can recesses.

38. In a machine for placing bails on cans, means for spreading apart the ends of the bail, and means cooperating with the spreading means for positioning the bail on the can.

39. In a machine for placing bails on cans, a bail spreader and means for positioning a can in relation to the spreader so that the bail ends after being passed over the spreader will engage with the can.

40. In a machine for placing bails on cans, a bail spreader comprising diverging guide-ways for the bail-ends, and means for registering a can with these guide-ways, whereby the bail ends after being passed over the spreader will engage with the can.

41. In a machine for attaching the ends of the bails to cans provided with bail-ears, a bail-spreader, and means for positioning a can in relation to the spreader so that the bail-ends after being passed over the spreader will engage with the bail-ears.

42. In a machine for attaching the ends of the bails to cans provided with bail-ears, a bail-spreader comprising diverging guide-ways for the bail-ends, and means for registering the bail-ears on the can with these guide-ways, whereby the bail-ends after being passed over the spreader will engage with the bail-ears.

43. In a machine for placing bails on cans provided with bail-receiving ears, means for separating the bail-ends and guiding them into engagement with the ears, and means cooperating with the guiding means for moving a bail into engagement with the ears.

44. In a machine for placing bails on cans, means for separating the bail-ends and guiding them into engagement with the can, and means cooperating with the guiding means for moving a bail into engagement with the can.

45. In a machine for placing bails with hooked ends on cans provided with recesses for receiving the hooked ends, means for spreading apart the bail-ends, and cooperating means for positioning the hooked ends in the recesses.

46. In a machine for placing bails with hooked ends on cans provided with recesses for receiving the hooked ends, means for separating the hooked ends and guiding them into the recesses, and means cooperating with the guiding means for moving the bail into engagement with the can.

47. In a machine for placing bails with hooked ends on cans provided with recesses for receiving the hooked ends, means for separating the hooked ends and guiding

them into the recesses, means for bringing the can and guiding means into operative relation with one another, and means cooperating with the guiding means for moving a bail into engagement with the can. 70

48. In a machine for placing bails on cans, a conveyor for the cans, a holder for a supply of bails, and means for moving and guiding a bail from the holder into engagement with a can. 75

49. In a machine for placing bails on cans, a holder for the bails, means for bringing the cans successively into operative relation to the bail-holder, and means timed with relation to the can-moving means for 80 moving and guiding a bail from the bail-holder into engagement with a can.

50. A machine for placing bails on cans, comprising a conveyor for the cans, means for advancing the conveyor from station to 85 station, means for feeding cans to the conveyor at one station, a bail-feeding means at a second station, and means at this second station for forcing a bail from the feeding means into engagement with the can then 90 at that station.

51. A machine for placing bails on cans, comprising a conveyor for the cans, means for advancing the conveyor from station to 95 station, means for feeding cans to the conveyor at one station, and means at a second station for positioning a bail on the can then at that station.

52. A machine for placing bails on cans, comprising a conveyor for the cans, means for advancing the conveyor from station to station, the cans being placed on the conveyor at one station, and means at a second station for automatically positioning a bail on the can then at that station. 100

53. A machine for placing bails on cans, comprising a holder for a supply of bails, a conveyor for supporting the cans and moving them successively into position adjacent the bail-holder, and means for moving 110 a bail from the holder into engagement with the can.

54. A machine for placing bails on cans, comprising a holder for a supply of bails, a plurality of can-supporting units adapted to bring a series of cans successively, one by one, into position adjacent the bail-holder, and means timed with the movement of the can-supporting units for moving and guiding a bail from the holder into engagement with the adjacent can. 115

55. In a machine for placing bails on cans, a slideway for the bails, means for pushing the bails one by one from the slideway into engagement with a can, and means for feeding the foremost bails on the slideway into position for engagement by the pushing means. 125
